US0D1033366S

(12) **United States Design Patent** (10) **Patent No.:** **US D1,033,366 S**
(45) **Date of Patent:** **** Jul. 2, 2024**

(54) **ELECTRICAL CONNECTOR**

(71) Applicant: **Molex, LLC**, Lisle, IL (US)

(72) Inventor: **Satoshi Tanaka**, Yamato (JP)

(73) Assignee: **Molex, LLC**, Lisle, IL (US)

(**) Term: **15 Years**

(21) Appl. No.: **29/812,756**

(22) Filed: **Oct. 25, 2021**

(30) **Foreign Application Priority Data**

Aug. 24, 2021 (JP) ..... 2021-018157 D

(51) **LOC (14) Cl.** **13-03**

(52) **U.S. Cl.**

USPC **D13/147**

OTHER PUBLICATIONS

Non-Final Rejection received for U.S. Appl. No. 17/411,125, mailed
on Feb. 1, 2023, 7 pages.

Primary Examiner — Christy Nemeth

Assistant Examiner — Justin M. Donaldson

(57)

CLAIM

The ornamental design for an electrical connector, as shown
and described.

DESCRIPTION

FIG. 1 is a first perspective view of an electrical connector
showing my new design;

FIG. 2 is a second perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines depicting the remainder of the electrical
connector form no part of the claimed design.

1 Claim, 8 Drawing Sheets
